 tion of Illinois

Original application April 3, 1935, Serial No.
 14,496. Divided and this application March 13,
 1937, Serial No. 130,739

17 Claims.

(Cl. 1—10)

This invention relates to the art of applying straps to boxes and has particular utility in the citrus industry for applying straps over the middle upper portion of lidded overfilled citrus shipping boxes and securing the ends of the straps to the sides of the boxes.

The general practice followed in the citrus industry in shipping fruit to market is to overfill the shipping containers, which comprise wooden boxes, so that when these are lidded, the middle of the lid is left bulging upwardly to accommodate the surplus fruit which lies above the upper limits of the box. This manner of packaging citrus fruits compensates for shrinkage of the fruit while it is enroute to market, so that when the boxes arrive at market, the fruit is snugly held in place in the boxes.

To secure this result, however, it has been found practically necessary to add a strap across the middle of the cover of each box after it has been lidded, which is applied to the cover with tension and then has its ends secured to the sides of the box. A number of machines have been provided for lidding overfilled citrus boxes; others have been provided for strapping overfilled citrus boxes which have previously been lidded; and still others have been provided for lidding and strapping overfilled boxes of citrus fruit in a single operation and requiring only one machine.

The last mentioned development is generally covered in the U. S. Letters Patent to H. D. Benson, No. 1,938,244, issued December 5, 1933, on a Method of and apparatus for securing covers to containers. In the Benson machine the strapper is located in the middle of a lidding machine and the lid pressing operation is performed by one mechanism, and the nailing of the lid and the applying of the strap is performed by an independently separate mechanism.

A later development of combined lidding and strapping machines is disclosed in the joint application of Hale Paxton et al., Serial No. 688,104, filed September 5, 1933, on an Automatic lid nailing and strapping machine. This machine had a single mechanism for pressing the lid on a box, nailing the ends of the lid to the ends of the box and applying the strap to the box and securing the ends thereof to the sides of the box. These functions were performed by mounting the

50 nail drivers of the strapping mechanism on the frame above the nailing table with the nail chucks suspended in slideable relation with the nail drivers, the nail chucks being held downwardly by yieldable spring means. The nailing table on which the box is positioned is capable of elevation

5 to lift the box upwardly with its ends in alignment with the chucks, so that the ends of the lid disposed beneath the chucks are pressed downwardly against the ends of the box due to the spring means before mentioned, resisting the upward movement of the chucks as the rising table presses the lid and box against said chucks. Completion of the pressing of the lid onto the box causes the upward movement of the table to be transmitted directly through the box 10 and the lid to the chucks so that the resistance of the spring means for holding these down is overcome and the chucks, each of which has been automatically supplied with a nail, are slid up over the drivers, thereby impaling the lid and 15 box ends on these nails with the same effect as if these nails were driven downwardly through the lid ends into the box ends.

While the lidding of the box is thus taking place, the strapping machine is engaged by the 20 middle of the lid so as to be lifted with the box, the latter movement accomplishing the operation of the mechanism on the strapper which secures the strap ends to the sides of the box so that as the box reaches its upwardmost position in the 25 machine, the lidding and strapping operations have been completed.

It is an object of my invention to provide an improved lidding and strapping machine having the same broad mode of operation as the machine disclosed in the aforesaid copending application.

It is a further object to provide such a machine in which the lidding and strapping functions are performed by a downward and upward 35 reciprocation of the cover pressing, lid nailing and strapping mechanisms disposed above the box.

Yet another object of my invention is to provide a novel strapping machine adapted to be 40 mounted as a unit over a box supporting table and capable of operation to apply a strap across the middle of the lid of said box and secure the ends of the strap to the sides of the box by virtue of relative vertical movement between said table 45 and said strapping machine as a unit.

Another object of my invention is to provide a novel strapping machine for strapping boxes varying in height.

Yet another object of my invention is to provide 50 a box strapping machine in which the strapping operation is effected by relative movement between the strapping machine and the box, and in which the approach of the box and strapping machine to accomplish the application of the 55

strap consumes an appreciably greater proportion of the time of each cycle of operation than the separation of said box and strapping machine following the strapping operation.

5 This application comprises a division carved out of my co-pending application on a Box nailng machine Ser. No. 14,496, filed April 3, 1935.

10 Other objects and advantages of the invention will be apparent from a study of the following specification, read in connection with the accompanying drawings, wherein

15 Fig. 1 is a front, elevational view of a lid-pressing, nailng and strapping machine constructed in accordance with my invention.

15 Fig. 2 is a side, elevational view of the machine illustrated in Fig. 1.

Fig. 3 is a detail, sectional view taken along line 3—3 of Fig. 1, illustrating the operative relation of the upper end of the overpacked box and 20 the parts of the machine at the initiation of a lid pressing and nailng operation.

Fig. 3a is a view similar to Fig. 3, illustrating the point in the lid pressing and nailng operation where the ends of the cover have just been 25 pressed against the ends of the box.

Fig. 3b is a view similar to Fig. 3a, illustrating the point when the lid pressing and nailng operation has just been completed.

Fig. 4 is a detail, sectional view taken along 30 the line 4—4 of Fig. 1 and illustrating the strapping machine of my invention.

Fig. 4a is a view similar to Fig. 4, illustrating the completion of a strapping operation by the strapping machine of my invention.

35 Fig. 5 is a fragmentary detail sectional view taken along the line 5—5 of Fig. 3 and illustrating the manner of reciprocably mounting the crosshead of my invention.

Fig. 6 is a detail sectional view of the power 40 controlling apparatus employed in connection with my invention.

Fig. 7 is a detail sectional view similar to Fig. 6, illustrating the control apparatus when starting the machine.

45 Fig. 8 is a view similar to Fig. 7, illustrating the manner of actuating the controls in reversing the operation of the machine after the machine has already been set into operation.

Fig. 9 is a detail view illustrating the relation 50 of the controlling pedals with each other and with the brake mechanism.

Fig. 10 is a fragmentary view illustrating the mechanism for elevating the nailng table incidental to a nailng operation when a box is to 55 be lidded which is of less depth than the standard box.

Referring to the drawings, I have illustrated my invention as embodied in a box-liddng and strapping machine particularly adapted to apply covers to overfilled orange boxes, or boxes in which other citrus fruits may be packed, though it will be understood by those skilled in the art that the machine illustrated and described herein is equally adaptable to the liddng of boxes for any desired contents, and particularly wherein the contents protrude above the top level of the box prior to the application of the lid thereto.

The machine comprises a suitable base formed from a pair of foot members 1 and 2 at opposite 70 sides of the machine and connected across the front and back of the machine by suitable cross bars 3 which may be formed of any suitable material, preferably fabricated steel structural members, such as angle iron. Rising vertically from 75 the foot member 1 is an upright 4 constituting a

vertical rail on which the lid-pressing, nailng and strapping apparatus may be reciprocably mounted. Similarly, at the opposite side of the machine, arising from the foot member 2, is an upright 5. The uprights 4 and 5 may be, and are preferably, formed from a section of channel iron or steel. The uprights have their upper ends connected together by means of a cross bar 6 to form the uprights and foot members into a substantially rigid rectangular structure extending 10 in the vertical direction.

Also mounted upon the foot member 1, slightly in advance of the upright 4, is a short upright 7, while a similar upright 8 is mounted upon the foot member 2 at the opposite side of the machine. The uprights 7 and 8 constitute guide-ways in each of which operates a bar 9, the upper end of the bar 9 at one end of the machine secured as at 10 to a cross tie 11, while the bar 9, at the opposite end of the machine is similarly 20 connected to a cross tie 12. The cross ties 11 and 12 constitute the end members of a substantially rectangular frame, the side rails 13 of which constitute bearing members in which are rotatably mounted a plurality of rollers 14 upon 25 which boxes to be lidded may be moved into and out of the machine. The rectangular frame formed by the members 11, 12 and 13 with the rollers 14, constitutes a section of roller conveyer 30 which may constitute a continuation of a suitable feeder conveyer by which the boxes are moved from the packing tables toward the liddng and strapping machine by mounting the liddng and strapping machine in the line of the feeder conveyer.

35 The rectangular frame 11, 12 and 13 is normally seated upon a stationary supporting structure including end bars 15 at opposite ends of the machine, interconnected by means of horizontal rails 16 all supported by and secured 40 directly to the uprights 7 and 8.

Thus in the normal operation of the machine the rectangular frame 11, 12 and 13 constitutes a nailng table upon which boxes to be lidded may be received and which will support the boxes in 45 position during the time the lids are applied to or nailed to or strapped upon the boxes. This nailng table being supported by the supporting structure 15 remains at the same level during the normal operation of the machine upon boxes of a given height and thus constitutes a stationary nailng table toward which the lid-pressing, nailng and strapping elements may be moved in 50 accomplishing the liddng and strapping operations, except as will be hereinafter described 55 when the nailng table may be lifted from its normal position to an elevated position to adapt the machine to apply lids to boxes of less height.

The lid-pressing and nailng mechanism includes, essentially, a reciprocating frame 17 from 60 which is suspended a nail chuck assembly 18 and nail driving punches 19.

The frame 17 is illustrated as being formed of a substantially rectangular frame, including a back rail 20 to which is secured a vertical bearing 65 member 21 at one end of the machine, and 22 at the opposite end of the machine. Extending horizontally from the bearing member 21 is a bracket 23, while a similar bracket 24 is secured to the bearing member 22, the forward ends of 70 the bracket 23 and 24 being secured together by means of a front rail 25. Each of the bearing members 21 and 22 is provided with a slide rail 22a, which extends vertically and is received in 75 vertical bearing grooves 22b formed in a metal

filler 22c secured to the inner surface of the uprights 4 and 5.

The left-hand end of the frame 17 constitutes a cross head structure for supporting lid-pressing and nailing mechanism for the left-hand end of a box, having secured to the bracket 23, a nail punch support 26 from which a plurality of nail punches 19 extend downwardly, the nail punches 19 having enlarged heads which are secured in 5 suitably slotted grooves in the support 26. Similarly the right-hand end of the frame 17 constitutes a cross head upon which a nail punch support 27 is secured to the bracket 24 and likewise suspends a plurality of nail punches 19 extending 10 vertically therefrom.

The nail chuck assembly at one end of the machine is suspended immediately below the nail punch support 26 and includes a nail chuck and lid engaging frame 28 having tubular guide bearings 29 thereon slidably mounted upon bearing rods 30 secured in turn directly to the bracket 23. The lower end of the bearing rods 30 extend 15 through and are secured to a secondary bracket 31 secured to the bearing member 21 and extending parallel to the bracket 23.

Secured upon the inner face of the chuck frame 28 are a plurality of nail chucks 32, one of which is aligned immediately below the nail punches 19 in the normal position, as shown in Fig. 3, and 20 extending into its associated nail chuck 32. Thus by movement of the nail chuck frame 28 relative to the crosshead 17 the nail punches 19 will be driven downwardly through the nail chucks to drive nails therethrough or the nail punches 19 25 will be refracted through the nail chucks 32 ready for the next nailing operation.

The relative movement between the nail chuck frame 28 and the crosshead 23 is accomplished by yieldingly mounting the nail chuck frame 28 30 upon the crosshead 17, and by securing to the inner face of the nail chuck frame 28 a pair of laterally extending suspension brackets 33 and 34, the suspension bracket 33 having a rearwardly extending lug 35 formed thereon to pivotally mount one end of a toggle link 36. The opposite end of the toggle link 36 is pivotally secured at 37 to the free end of a second toggle link 38, the opposite end of which is secured at 39 to a downwardly dependent lug 40 as formed upon a cross strap 41 secured at its opposite ends to the 35 rear bar 20 and the front bar 25 of the crosshead assembly.

The suspension bracket 34 likewise has a forwardly extending lug 42 which pivotally mounts one end of a toggle link 43, the free end of which 40 is pivotally secured as at 44 to the free end of a toggle link 45, the opposite end of which is secured to a lug 46 depending downwardly from the cross strap 41. The pivotal points of the free ends 45 of toggle links 36, 38 and the pivotal point of the free ends of toggle links 43, 45, are interconnected by means of a tension spring 47 normally under tension to draw the midpoints of toggle links 36, 38 and 43 and 45 toward each other. The spring 47 may be secured to the pivot points 37 and 44 50 by any suitable means, as by means of a clevis 48 secured to the end of the spring 47.

The mounting of the nail chuck frame 28 by means of the opposed toggle links 36, 38 and 43, 45, normally urged toward each other by means 55 of the spring 47, as described, constitutes a yielding mounting between the crosshead 17 and the nail chuck assembly in which the force required to cause the yielding between the nail chuck assembly and the crosshead to occur may be set or

adjusted at any desired value by determining the tension of the spring 47. It will be further observed that as the crosshead 17 is moved downwardly to bring the nail chucks into engagement with the cover of a box, the resistance offered by the cover of the box to further downward movement of the nail chuck assembly 28 will be sufficient to overcome the tension of the spring 47, thus permitting the crosshead 17 to continue its downward movement without causing further downward movement of the nail chuck assembly 28.

However, as the nail chuck assembly and the crosshead 17 are moved toward each other, the midpoint of the toggle links 36, 38 will tend to move outwardly away from the midpoint of the toggle links 43, 45, and, similarly, the midpoint of the toggle links 43, 45 will move outwardly away from the midpoint of the toggle links 36, 38. This relative movement of the toggle links 36, 38 15 from the toggle links 43, 45 will tend to further stretch the spring 47, thus increasing the force exerted by this spring. However, the force exerted by the spring will be applied to the nail chuck assembly 28 through the toggle links 36 20 and 43 which will be moved to more acute angular positions relative to the nail chuck frame 28. By plotting the horizontal and vertical forces exerted through the toggle links 36 and 43, it will be observed that as the nail chuck assembly 28 25 approaches the crosshead 17 the vertical component of the forces exerted by the spring 47 will be greatly reduced and by selecting the length of the toggles 36, 43 so proportioned to the strength 47, the vertical component of the force 30 exerted by the spring on the nail chuck frame 28 may be reduced by an amount which substantially equals the increased tension of the spring 47. Thus the maximum amount of vertical force 35 which can be exerted upon the nail chuck frame 28 to compress covers down upon the box ends may be adjusted by the initial tension on the spring 47 and irrespective of the distance through which the crosshead moves in bringing the nail chuck frame 28 into contact with the end of the 40 cover and driving the nails through the cover, the pressure which is exerted by the nail chuck frame on the cover cannot vary or exceed the predetermined amount for which the spring 47 45 has been selected.

It will also be observed that while the crosshead 17 may be moved through the same distance upon each of its operations, the chuck frame 28 can never exert more than a predetermined force 50 upon the cover and upon the box upon which it is operating. Thus the pressing operations may be accomplished by the movement of a single crosshead 17 to spring the cover ends down over the overpacked or protruding fruit to bring the cover end into contact with the box ends with 55 only a predetermined pressure exerted upon the cover, which pressure will not be increased should the overpack be greater in one box than in another box operated upon. The main advantage, however, is the fact that the strain on the machine assembly and the power required to press the cover down is not increased during the nail driving operation.

The nail chuck frame 28 may be employed to initially support the covers 49 prior to their application to the box and may also support suitable tucking mechanisms 50 which may operate to tuck in or press in the protruding fruit at the end of the box prior to the springing of the cover ends down upon the box ends. For this latter 60 65 70 75

purpose, the chuck frame 28 is provided with a pair of downwardly extending lugs 51 and 52 between which is pivotally mounted the tucker 50 so arranged as to extend below the ends of the cover 49 to be brought into contact with the protruding fruit at the ends of the box as the chuck frame 28 is moved down toward the box. As the chuck frame 28 continues its movement, the tucker 50 will be engaged by the end of the box and rotated upwardly about its pivotal mounting to withdraw the tucker 50 from its position between the cover ends and box ends and thus permit the cover ends to spring down into contact with the box ends. Also the forwardly extending brackets 33 and 34 may be employed for the mounting of additional press shoes 53 spaced from the nail chucks 32 to engage the cover between its extreme ends and the center thereof to assist in the shaping of the cover as it is bowed down over the extending or protruding fruit.

It will be observed that at the opposite end of the machine a similar nail chuck frame 54 is provided mounted upon vertical rods 55 corresponding in all respects to the nail chuck frame 28 and its mounting upon the rods 30. Similarly, the nail chuck frame 54 is provided with a similar toggle link and spring assembly indicated generally by the reference character 56 corresponding in all respects to the toggle link and spring mounting for the nail chuck frame 28 to mount the nail chuck frame 54 at that side of the machine for the same relative movement and to exert the same constant compressive forces, irrespective of the movements of the crosshead 17 relative to the nail chuck frame 54.

With the nail chuck frames 28 and 54 secured to the crosshead 17, as described, a single movement of the crosshead 17 toward the box supporting table 11, 12 and 13 will first spring the cover ends down into contact with the box ends and then, by further downward movement of the crosshead 17, the nails will be driven by the nail punches 19 into and through the cover ends and into the box ends to secure the cover to the box, while return upward movement of the crosshead 17 will first elevate the nail punches 19 until the bearing members 29 abut upon the bracket 31 and then further upward movement of the crosshead 17 will lift the chuck frames 28 and 54 away from the now lidded box, freeing the box for movement out of the machine.

The crosshead 17, as hereinbefore described, is slidably or reciprocably mounted upon the uprights 4 and 5 and is arranged to be moved through a cycle of operations from its normal elevated position as shown in Fig. 1 down toward the box supporting table 11, 12, 13 to complete the pressing and nailing operations, and then back to its elevated position as shown in Fig. 1, by means of suitable power apparatus which includes a motor or similar prime mover 57 which may be mounted in any suitable position upon the base of the machine. The motor shaft 58 drives a pinion 59 which is meshed with a gear 60 having a laterally extending crankpin 61 pivotally mounting a sleeve 62.

The sleeve 62 is slidably assembled upon a cylindrical drive bar 63 rigidly and radially secured to a drive shaft 64 extending longitudinally of the machine and journaled in suitable bearings 65 at opposite ends of the machine which are in turn mounted upon cross braces 66 extending between the uprights 4 and 7 and uprights 5 and 8 respectively. Thus one complete rotation of

the gear shown in Fig. 2, from its normal rest position as shown in Fig. 2, will cause the drive shaft 64 to be moved in a clockwise direction during substantially 240° of such revolution, while during the remaining 120° of said revolution the shaft 64 will be moved in a counter-clockwise direction.

By referring particularly to Fig. 1 it will be observed that near the right hand end of the drive shaft 64 there is rigidly secured to the drive shaft a lever 67 having one arm thereof extending rearwardly of the machine to be pivotally engaged as at 68 with the lower end of a connecting rod 69. The upper end of the connecting rod 69 is pivotally secured as at 70 to an angle bar 71 secured between the bearing members 21 and 22 on the crosshead 17. Thus the movement of the drive shaft 64 first in a clockwise direction and then in a counter-clockwise direction will be transmitted through the lever 67 and through the connecting rods 69 to first move the crosshead 17 downwardly toward the box-supporting table 11, 12 and 13 and then upwardly away from the box-supporting table to return the crosshead 17 to its normal elevated position. A lever 72 is similarly secured to the drive shaft 64 near the opposite end thereof and is connected by a connecting link 73 to the angle bar 71 at the side of the machine opposite the connection of the connecting rod 69.

By reason of coupling the gear 60 to the drive shaft 64 through the sleeve 62 and the slide bar 63, it will be observed that one complete revolution of the gear 60 will move the crosshead 17 downward and then back to its normal position, the downward movement occurring at a relatively low speed; that is, with the gear 60 rotating at a constant speed throughout one revolution. The downward movement of the crosshead 17 will occur during 240° of the revolution of the gear 60, while the re-elevation of the crosshead 17 to its normal position will occur during the final 120° of movement of the gear 60, this return movement occurring at a greatly increased speed over the speed of downward movement of the crosshead 17. It will also be observed that by reason of the connection of the gear 60 to the slide bar 63 that the greatest leverage is exerted by this connection during the downward movement of the crosshead 17 thus providing for the pressing forces which are necessary to draw the crosshead 17 and the nail chuck frames 28 and 54 down against the resistance of the box, its contents, and its cover and also with sufficient force to insure the driving of the nails through the cover and into the box ends, while the return movement of the crosshead 17, constituting merely the lifting of the crosshead, the nailing mechanism and the pressing mechanism to a position free of the box, may be accomplished at the higher speed, at which time the leverage provided by the coupling of the gear 60 to the slide bar 63 will be much reduced.

The motor 57 may be controlled in any suitable manner to apply power to the gear 60 whenever it is desired to perform a lidding operation upon a box. However, I prefer to arrange a switch 74 in circuit with the motor 57, arranged to be closed to start the motor 57 only when it is desired to perform a lidding operation.

The switch 74 may be suitably controlled, as indicated in Fig. 6, by means of a foot pedal 75 constituting one end of a foot lever 76. The lever 76 extends forwardly and rearwardly of the machine and is pivoted upon a rod 77 near the rear

of the machine. The foot lever 16 extends immediately above a switch plate 78 pivotally mounted above the switch 74 so that when the foot pedal 75 is depressed by an operator of the machine, the switch plate 78 will be rotated about its pivot to depress and close the switch 74. A suitable spring 79 may be employed to normally hold the foot pedal 75 and foot lever 16 in its normal or elevated position, the spring 79 being illustrated as surrounding a bolt 80 rigidly secured to the frame of the machine and passing through an opening 81 in the foot pedal 75.

Since it is desired that the gear 60 should always come to rest at the completion of one operation of the machine with the parts in the position shown in Figs. 1 and 2, namely with the crosshead 17 in its normal elevated position, I arrange a brake for the motor 57 which will apply a braking force thereto to the motor whenever the foot pedal 75 is released.

By referring particularly to Figs. 7 and 9, it will be observed that the brake apparatus includes a brakedrum 82 secured upon the motor shaft 58 upon which may bear a brake-shoe 83 having a suitable brake-lining 84 thereon to engage the drum. The brake-shoe 83 is illustrated as having an arm 85 extending forwardly of the machine to pivotally engage, as at 86, with an up-standing lever 87 rigidly secured to the rod 77. The rod 77 is also provided with a forwardly extending lever 88 rigidly secured thereto, the lever 88 projecting parallel to the longitudinal axis of the foot lever 16 and disposed immediately below a laterally extending lug 89 formed upon or secured to the foot lever 16. Thus whenever the foot lever 16 is depressed to close the switch 74 to start the motor, such depression of the lever 16 will cause a depression of the lever 88, partially rotating the rod 77 and drawing the brake-shoe 83 out of engagement with the brake-drum 82. The lower surface of the brake-shoe 83 is adapted to slide rearwardly and forwardly of the machine and normally rests upon a slide bearing, illustrated herein as constituting the head of an adjusting screw 90 by which the brake-shoe 83 may be properly centered relative to the brake-drum 82.

The distance through which the brake-shoe 83 will move upon the depression of the foot lever 16 may be regulated by means of a suitable adjusting screw 91 extending through the lug 89 into engagement with the lever 88. Also, the amount of pressure which is exerted upon the brake-shoe 83, tending to apply it to the brake drum 82, may be controlled by forming an extension 92 on the lower end of the lever 87 and interposing a brake-spring 93 between this extending end of the lever 87 and some stationary portion of the machine illustrated as an abutment 94 (see Fig. 7).

Since it is essential that the gear 60 must be stopped when the parts of the machine have arrived at the positions shown in Figs. 1 and 2, I provide a cam 95 upon the shaft 96 upon which the gear 60 is mounted, the cam 95 having a low level 97 thereon which will permit the foot lever 76 to return to its elevated position when the cam 95 has arrived in the position shown in Figs. 6 and 7. The cam 95 may also be provided with a high level 98 extending about a portion of its periphery to prevent the return of the foot lever 76 to its normal or motor-stopping position if the operator should release the same immediately before the gear 60 has completed its revolution.

In the lidding of a box with the parts of the

machine thus far described, the box will be brought in over the feeder conveyor which furnishes the boxes to the machine and from this conveyor the box will be drawn in either by power or by hand onto the nailing table 11, 12 and 13, 5 preferably being stopped in a central position with the box ends aligned directly below the nail chucks 32 at opposite ends of the machine by means of a suitable stop 89. A cover 49 may then be placed above the box, preferably by permitting 10 the same to rest upon the inwardly extending tuckers 50. The operator may then depress the pedal 75, closing the switch 74 and starting the motor 57 which will, by rotation of the gear 60, draw the crosshead 17 down toward the box, 15 bringing the cover down toward the box, while the tuckers 50 engage and press inwardly any protruding fruit at the ends of the box. When the cover rests upon the overpack, or fruit extending above the top level of the box, it will be 20 engaged by this fruit so that pressure must then be applied to the ends of the cover to spring them down into contact with the box ends. This pressing operation is accomplished by the continued downward movement of the crosshead 17 25 bringing the nail chuck frames 28 and 54 down upon the ends of the cover, the pressure exerted being determined by the tension of the springs 47.

During the pressing of the cover down into contact with the box ends, it may be discovered 30 that some of the fruit is in danger of being crushed or pinched between the cover and the top edges and sides and ends of the box, in which event the operator must be able to stop the further downward movement of the crosshead 17 35 and permit this crosshead to re-elevate while the operator adjusts the fruit within the box. This may be accomplished by providing a motor-reversing mechanism, as hereinafter described. However, should the pressing operations be 40 accomplished without mishap or danger of injury to the fruit, the continued downward movement of the crosshead 17 will cause the nail punches 19 to continue their downward movement after the chuck frames 28 and 54 have been stopped 45 by the engagement of the cover ends with the box ends and the complete nailing operation may then be completed by the continued downward movement of the crosshead 17.

It will be observed, however, that as soon as the 50 pressing operations are completed and the nailing operations start,—that is as soon as the chuck frames 28 and 54 have sprung the cover ends into contact with the box ends, and therefore cannot move downwardly any further, the nailing 55 operations must continue to completion.

For this reason I provide the low level 97 of the cam 95 as extending throughout that portion of the revolution of the shaft 96 as will correspond to the ordinary pressing operation; that is, this 60 low level of the cam will extend throughout that portion of the movement of the crosshead 17 which is required to bring the cover ends down into contact with the box ends.

While the low level of the cam 95 is presented 65 to the roller 100 of the foot lever 76, the foot lever 76 may be released and by reason of the spring 79 will return to its normal, or switch-open position. However, the high level 98 of the cam 95 extends throughout the remaining portion of the periphery of the cam, starting at the point in the revolution of the shaft 96 at which the pressing operations should be complete and the nailing operations should start. When the high level 98 of the cam is presented to the roller 100, release of the 75

pedal 76 by the operator will not return the foot lever to its switch-open position, this lever being held depressed by the high level 98 of the cam until the rotation of the shaft 96 has been completed, at which time all of the parts of the machine are again in their normal positions, as shown in Figs. 1 and 2.

However, as hereinbefore explained, if, during the pressing operations it is discovered that the fruit is in danger of being crushed or bruised or that the box is liable to be damaged because it is not properly centered, or has some defect, the operator must be enabled to stop the machine and to reverse the movement of the crosshead 17 to permit the operator to correct the defect and avoid the damage. For this reason I have provided a second switch 101, preferably arranged in the same case 102 which houses the switch 74 and preferably lying immediately below the pivoted plate 78 but on the opposite side of the pivot thereof. The switch 101 is connected in circuit with the motor 57 in such manner that when this switch is closed current is supplied to the motor in such manner as to cause reverse rotation of the motor. The switch 101 is arranged to be actuated by a reversing pedal 103 similar in general construction to the pedal 75 in that the pedal 103 constitutes the extending end of a reversing foot lever 104, the rear end of which is formed in a relatively T-shape, the head 105 of the T constituting a pivotal support for the foot lever 104 by engaging the rod 77.

It will be understood that the foot pedal 103 will only be actuated to reverse the motor 57 when it has been discovered that injury is likely to occur to the fruit or to the cover, at which time the foot pedal 75 will have been released, and it is necessary that the depression of the foot pedal 103 shall release the brake 83 from the motor shaft in the same manner as though the foot pedal 75 had been depressed, and for this purpose I provide an outstanding lug 106 upon the foot lever 104 which extends immediately above a second lever 107 corresponding in all respects to the lever 88.

An adjusting screw 108 may be provided in the lug 106 to make contact with the lever 107 so that when the pedal 104 is depressed the lever 107 will be depressed and will rock the shaft 77 in the same direction and to substantially the same extent as this shaft is rocked by actuation of the foot pedal 75. Thus the brake-shoe 83 will be withdrawn from the brakedrum 82 at the same time that the pedal 103 closes the reversing switch 101.

Since at any time during the pressing operations,—that is, during the first portion of the cycle of operations of the crosshead 17, the pedal 103 must be free to be depressed to reverse the motor, but when the nailing operations are started the reverse operations of the motor must not be permitted, I provide a second cam 109 on the shaft 96 which has a low level 110 extending throughout a portion of its periphery, so arranged, relative to the low level of the cam 95, as to present its surface to a roller 111 formed upon an extending end of the head 105 of the T-shaped reversing lever 104. Thus during the time at which the low level 97 of cam 95 is presented to roller 100 on foot lever 76 (that is during the entire pressing operations), the low level 110 of the cam 109 will be presented to its roller 111, leaving the pedal 103 free to be depressed to reverse the motor at any time.

The cam 109, however, is provided with a high

level 112 which will be presented to the roller 111 at about the same time that the high level 98 of the cam 95 is presented to its roller 100 so that at the time the foot lever 76 is prevented from returning to its switch-open position the foot lever 104 and its pedal 103 will be positively prevented from operating to reverse the motor.

By referring particularly to Fig. 6 it will be understood that when the shaft 96 has been moved through one complete cycle of operations the high level 112 of the cam 109 will be just ready to pass the roller 111, while the high level 98 of cam 95 will have just passed the roller 100. Thus at the end of the cycle of operations foot lever 76 is free to return to switch-off position, while the reversing foot lever 104 is prevented from being operated until after the start of the next cycle of operations.

Since in the packing of certain articles it may be desired to employ the same machine for applying lids to boxes of one height and also to boxes of another height, I prefer to adjust the machine to apply the lids to boxes of the greatest height when the nailing table 11, 12 and 13 is in its normal or lowermost position, and to provide means for lifting the nailing table to an elevated position whenever boxes of a lesser height are to be lidded in the machine. As hereinbefore explained, the nailing table 11, 12 and 13 is mounted upon the bars 9 which are slidably engaged in uprights 7 and 8. A cross bar or rod 113 is secured between the bars 9 by which force may be exerted to elevate the table 11, 12 and 13.

I prefer to cause the table 11, 12 and 13 to be elevated by power mechanism, which power may be supplied from the motor 57 upon each operation of the machine, as by extending the levers 67 and 72 forwardly of the machine to constitute arms 114 on the lever 67 and 115 on the lever 72, respectively, which may be employed to perform the table-elevating operations.

By referring particularly to Figs. 1, 2 and 10, it will be observed that upon each of the uprights 7 and 8 I provide a forwardly extending bracket 116 in which is journaled a shaft 117 extending across the front of the machine. Near each right-hand end of the shaft 117 I pivotally mount a link 118 which is in turn connected as at 119 to a second link 120. At the opposite side of the machine a similar link construction, including a link 121, is pivoted upon the shaft 117 and is connected at 122 to a second link 123. The links 120 and 123 are interconnected across the front of the machine by means of a cross bar 124 so that assembly of the links 118-120 and 121-123 at opposite sides of the machine are tied together as a single unit. The links 118-120 and 121-123 form a folding elevator mechanism which, when the machine is operating only upon boxes of the greatest height for which the machine is designed, may be folded as indicated in Figs. 1 and 2, out of the path of movement of the extending ends 114 of the lever 67.

However, when it is desired to cause the nailing table to be elevated to the position shown in Fig. 10, all that is necessary is to lift the cross bar 124 to the position shown in Fig. 10, engaging the ends of links 120 and 123 with the cross head 113 extending between the cams 9 for the table 11, 12 and 13. Preferably, the ends of the links 120 and 123 are provided with a spring clip 125 to engage above the cross rod 113 to hold the link assemblies in engagement therewith. When the link assemblies have been removed to the operative position shown in Fig. 10, it will be

observed that the links 118 and 121 lie in the path of movement of extending ends 114 and 115 of the levers 67 and 72 and if desired these extending ends of the levers may be provided with 5 rollers 126 to form a roller bearing at this point of engagement. Thus, when a box of reduced height, for instance one-half the height of the normal box to be used on the machine, is placed upon the nailing table 11, 12 and 13, the link 10 assemblies may be moved into the position shown in Fig. 10 to engage the cross rod 113. Then upon the depression of the pedal 74 to move the crosshead 17 downwardly the nailing table 11, 12 and 13 will be simultaneously moved upwardly 15 toward the approaching crosshead 17. By properly selecting the length of the links 118—120 and 121—123, the amount of upward movement of the nailing table may be made any desired value to 20 accommodate a predetermined reduced height box.

After the reduced height boxes have been lidded and it is desired to continue the lidding of normal sized boxes, the link assemblies may be disconnected from the cross arm 115 and 25 folded out of the way, thus returning the machine to its normal position upon normal sized boxes.

While the lidding machine thus far described 30 may be employed for applying lids to boxes and for securing these lids to the boxes, it may also be desired to have a strap across the center of the box and this operation may be performed in a separate machine such as that illustrated and described in the United States Letters Patent No. 35 1,777,474 issued to George D. Parker, or a strapping head may be applied directly to the machine herein described to be actuated by movement of the crosshead 17 to thus apply the straps to the boxes, while they remain in this machine.

40 I have illustrated a strapping mechanism particularly in Figs. 1, 2 and 4 as comprising a press-shoe 130 which may be, and preferably is, formed of a pair of plates 131 and 132 extending parallel to each other and transversely of the nailing table 11, 12 and 13, these plates being spaced apart by suitable spacing members 133 and secured together by means of suitable bolts 134. The space between the plates 131 and 132 of the press-shoe is preferably just sufficient to accommodate therebetween a wire strap 135 which may be formed as illustrated and described in the patent to George D. Parker, No. 1,777,474 herein-before referred to as a length of wire, the ends of which are inturned as indicated at 136 and 45 sharpened to constitute driving ends by which the straps may be secured to the box. The press-shoe 130 is mounted upon the crosshead 17, as by means of a pair of outstanding lugs 137 and 138 formed upon the plate 131. Pivotally secured 50 to the lug 137 is a link 139, the free end of which is pivotally secured as at 140 to a second link 141, the opposite end of which is secured to a downwardly depending lug 142 formed upon a cross strap 143 extending between and secured to the cross bars 20 and 25. Similarly the lug 138 55 has secured thereto a link 144, the free end of which is pivoted at 145 to a second link 146, the opposite end of which is secured to a downwardly extending lug 147 also secured to the cross strap 143.

Interposed between the pivot points 140 and 145 60 is a tension spring 148 similar in all respects to the tension spring 47 described with reference to the mounting of the chuckframe 28 so that the 65 assembled toggle links 139—141 and 144—146 with

the spring 148 constitute a mounting for the press-shoe 130 by which downward movement of the crosshead 17 applies downward force upon the press-shoe 130 until a predetermined resistance is built up in the protruding fruit and the cover of the box, after which the press-shoe 130 will not be moved to a further downward position but such pressure will be maintained upon the cover of a constant value during the continued downward movement of the crosshead 17. 10

Means may be provided upon the press-shoe 130 for bending the ends of the strap 135 down over the side edges of the box-cover and for driving the pre-formed ends 136 into the side walls of the box to secure the strap thereto. This driving means is illustrated herein as comprising a driving element 149 pivoted as at 150 between the plates 130—131, constituting the press-shoe 130. One end of the driving element 149 extends upwardly above the upper limits of the plates 20 131—132 to connect with an operating link 151 which extends laterally of the machine to engage a bellcrank 152 pivoted at 153 upon a bracket 154 mounted upon a vertical bar 155 extending between the cross bars 20 and 71. Similarly, a 25 driving element 156 is pivoted at 157 between the plates 131—132, the extending end of which is connected by means of a link 158 to a second bellcrank 159 pivoted upon the same pivot 153 but arranged to operate reversely to the movement of 30 the bellcrank 152. The driving elements 149 and 156 are normally held in their retracted positions, as shown in Fig. 4, by means of a suitable tension spring 160 interposed between upstanding ears 161 on link 151 and ears 162 on link 158. 35

I prefer to employ the downward movement of the crosshead 17 both as a means for applying pressure to the press-shoe 130 to compress the cover down upon the box during the time the strap is applied thereto, and also for the purpose 40 of providing such power as may be necessary to bend the ends of the strap around the edges of the box and to drive the ends of the strap into the box. For this purpose I employ the movement of the bracket 154, which, being secured to and 45 movable with the crosshead 17, is moved downwardly through the same distance as the crosshead 17. The bracket 154, mounting the two bellcranks 152 and 159, is provided at their lower ends with a pair of rollers 163 and 164, respectively, which extend toward each other in such 50 manner that under the force exerted by the spring 160 the rollers 163 and 164 are brought into engagement with each other. Mounted upon any suitable stationary portion of the machine, as 55 upon an angle brace 165 constituting one of the braces employed for the frame of the machine, I mount a wedge 166 substantially aligned with the meeting faces of the rollers 163 and 164 so that as the crosshead 17 moves downwardly bearing 60 the bellcranks 152 and 159 downwardly, they engage the wedge 166 and are separated by it to move the link 151 forwardly of the machine, and the link 158 rearwardly of the machine, to swing the driving elements 149 and 156 about their pivots. In order that the inward movement of the driving elements 149—156 shall not crush or injure the contents of the box, or the box, I prefer 65 to mount the wedge 166 by suitable yielding means, which, while it will exert sufficient pressure to insure the complete driving of the strap ends into the box, will permit a yielding of the forces exerted upon the driving elements should the overpack of the fruit be of abnormal height. 70 This spring mounting is illustrated in Fig. 4 as 75

constituting a spring 167 surrounding a post 168, the upper end of which constitutes the mounting for the wedge 166, while the lower end of the post 168 extends through a bracket 169, being held against removal therefrom by means of a head 170 formed upon the post 168. The spring 167 engages the upper surface of the bracket 169 at one of its ends, while the opposite end of the spring engages a suitable adjusting nut 171 10 threadedly secured upon the post 168 so that by adjusting the nut 171 toward and away from the bracket 169 the compression force of the spring 167 may be given any desired value.

It will also be observed that the spring and post 15 mounting of the wedge 166 permits this wedge to be rocked slightly relative to the support bracket 169 so that should greater resistance be offered to the driving of one end of the strap into the box than is offered to the opposite driving end of the 20 box, the wedge 166 may yield laterally of the machine and thus insure that sufficient pressure is exerted to complete the strap-applying operations without crushing or injuring the box.

It will also be observed that I have provided a 25 machine in which lidding, pressing and strapping operations may be performed at a sufficiently low speed to permit the operator of the machine to correct any improper operations and to prevent damage to the fruit or the box during the pressing of the strapping head upon the box, but in which a rapid return of the parts to their normal box-releasing position may be accomplished to free the box from the machine without loss of time.

30 As illustrated herein, the strapping mechanism may include also a magazine or holder for a supply of straps which may automatically be fed from the holder into a position between the plates 131 and 132 in response to the operations of the 35 machine in the same manner as described in the George D. Parker Patent No. 1,777,474. Such magazine is illustrated at 180, which is supported upon a bracket 181 secured to the left-hand plate 132 of the press-shoe. Extending rearwardly 40 from the plate 132 is a second bracket 182 which has a vertical extension 183 thereon constituting a bearing member in which is pivoted as at 184 a lever 185, the upper end of which brings a roller 186 in the path of movement of a cam plate 187 secured to the crosshead 17. Thus whenever 45 the strapping mechanism is actuated to apply a strap to a box, causing a relative motion between the press-shoe 130 and the crosshead 17, the engagement of the lever 185 by the cam plate 187 will cause actuation of the feeding mechanism, such as is shown and described in the said George 50 D. Parker Patent No. 1,777,474.

With the parts of the machine as shown in Figs. 1 and 2, a packed box ready to be lidded and 55 strapped is fed into the machine so as to rest on the rollers 14 of the nailing table. A lid 49 is now inserted in place supported at its ends on the tuckers 50. The operator now steps on the pedal 75 which energizes the motor 57, causing rotation 60 of the gear wheel 60, which operates through the slide sleeve 62 and arm 63 to rock the shaft 64, thus pulling down on the pitmans 69 and lowering the cross head 17 carrying the nailing units and strapper of the machine. As the cross head thus 65 moves downwardly the overfilled contents of the packed box in the machine are contacted by the cover 49 so as to support the latter, and with the result that the cover shaping members 53 engage the cover and, cooperating with the nail chucks 70 75 18, which engage the ends of the cover, arch the

latter over the protruding contents of the box with the ends of the cover pressed downward onto the ends of the box. Just prior to the consummation of this action the downward movement of the cross head 17 brings the end tuckers 50 into engagement with the box thus 5 rocking these end tuckers upwardly and outwardly from between the ends of the box and the ends of the cover.

The strapping machine is so located on the 10 cross head 17 that the press shoe 130 comes into engagement with the cover 49 of the box and shapes this cover transversely beneath a strap 135 carried by the press shoe just as the ends of the cover 49 are brought into contact with the 15 ends of the box in position for nailing thereto. Following the arrival at this step in the lidding and strapping operation, the cross head 17 continues to move downward. The downward movement of the nail chucks 18 and the strapper press 20 shoe 130, however, having been halted by their engagement with the cover of the box, the springs 47 and 148 are caused to yield and the toggles 25 supporting these springs to collapse somewhat. The angles at which the members of these toggles 25 are connected to the cross head 17 and to the nail chuck assemblies 18 and press shoe 130 are such that the downward resultant of pressure by the springs 47 and 148 are caused to remain substantially constant throughout the relative movement 30 between the cross-head 17 on the one hand and the nail chuck assemblies 18 and the press shoe 130 on the other hand.

The relative movement just noted results in the 35 nail drivers 19 sliding downwardly through nail chucks 32 so as to drive nails therefrom through the ends of the cover and into the ends of the box. It also results in the pivot 153 (see Fig. 4a) moving downwardly with the cross head 17 until the rollers 163 and 164 of the levers 152 and 159 40 carried on that pivot engage with opposite sloping edges of the cam member 166 thus swinging the strap end drivers 149 and 156 into strap driving positions, as shown in Fig. 4a.

The cross head 17 reaches its lowermost position just as the downward swing of the arm 63 ceases and the slide sleeve 62 commences to rock this arm back to its original upward position as shown in Fig. 2. The return upward of the arm 62 is transmitted through the shaft 64 and the pitmans 69 to the cross head 17 so that the latter is returned to its upwardmost position as shown in Figs. 1 and 2 leaving the box in the machine completely lidded and strapped.

As the cross head 17 rises and the rollers 163 55 and 164 are lifted out of contact with the cam plate 166, the spring 160 returns the strap end drivers 149 and 156 to their retracted positions as shown in Fig. 4 and the strapper magazine 80 is automatically actuated to deliver another strap 60 135 into the guide recesses 133 provided in the cover shaping bar 130. The box just lidded and strapped having been moved from the nailing table, the machine is again ready to receive a packed box to be lidded and strapped.

The cross head 17 reaches its uppermost position just as the gear 60 has completed a single revolution. This coincides with the arrival of the low level 97 of the cam 85 opposite the roller 100 which permits the latter to ride onto the low 70 level thus swinging the arm 76, shutting off the switch 102, applying brake shoe 83 to brake drum 82 of the motor 57 and stopping the entire machine.

While I have shown and described the pre- 75

ferred embodiment of my invention, I do not wish to be limited to any of the details of construction shown herein, except as defined in the appended claims.

5. I claim:

1. In a box-strapping machine, the combination of: a table for supporting the box; a crosshead mounted above said table and vertically reciprocable relative thereto; a strapping head supported on said crosshead and including means for applying a strap across the lid of a box on said table and flexing the edges of said lid downward and means for securing the ends of the strap to the sides of said box; means for reciprocating said crosshead vertically; and means responsive to said reciprocation to actuate said strap-applying means and strap end securing means.

2. In a machine for strapping a cover to an overfilled packed box by a strap applied across a middle portion of said cover in a plane disposed transversely of said cover, the combination of: a frame; a table on said frame for supporting said packed box in upright position with a cover disposed thereover in readiness to be strapped to said box; a crosshead vertically reciprocable on said frame; means to confine opposite end portions of a strap in said plane and adjacent opposite sides of said box; means to secure the strap ends to said box sides; a member extending across said cover and uniting said aforementioned means in a vertically movable strapper unit, said unit being mounted on said crosshead; means for lowering said crosshead to shift said strapper unit downward into proper relation with said cover and said box to perform a strapping operation; and means responsive to said downward movement of said crosshead to actuate said strap securing means to cause the latter to secure the strap ends to the sides of said box.

3. A combination as in claim 2 in which said strapper unit member is adapted to shape the cover of the box laterally at the time said strapper unit applies the strap to the box.

4. In a machine for strapping a cover on an overfilled packed box having a partition, the combination of: a table for supporting said packed box in upright position with a cover positioned thereover; a crosshead disposed above said table and vertically reciprocable relative to the latter; means to confine opposite end portions of the strap in the plane of said partition and to then secure the strap ends to said box; cover shaping means extending across said cover and connecting said aforementioned means to form a strapper unit; means for supporting said strapper unit on said crosshead so as to be yieldable vertically relative to the latter; means for urging said unit downward to its lowermost limit of movement relative to said crosshead; means for causing vertical reciprocation of said crosshead; and means responsive to said vertical reciprocation to operate said strapper unit to cause the latter to apply a strap across the cover of said box, to shape said cover, and to secure the strap ends to opposite sides of said box.

5. In a machine for lidding and strapping boxes, the combination of: means for positioning a box in said machine; means for nailing the ends of the lid on said box while so positioned; means for applying the strap across said lid between its ends and securing it to sides of said box while the latter is so positioned; and a crosshead for carrying said nailing means and strapping means and operating the means so carried by vertical reciprocation of said crosshead rela-

tive to said box to accomplish the functions aforesaid of said nailing and strapping means.

6. In a machine for applying straps to covers of boxes, the combination of: a table for supporting a packed box having a cover disposed thereover; a press shoe; means suspending said press shoe from said cross head for yielding movement relative to said cross head; means for reciprocating said crosshead toward and away from said table to bring said press shoe into pressural engagement with said cover; means for exerting a force of substantially constant value between said cross head and said press shoe, said force opposing said yielding movement in all the positions of said press shoe relative to said cross head; and means for securing a strap across the cover of said box, while pressure is being applied to said cover by said shoe.

7. In a machine for applying straps to covers of boxes, the combination of: a table for supporting a packed box having a cover disposed thereover; a press shoe; means suspending said press shoe from said cross head for yielding movement relative to said cross head; means for reciprocating said cross head toward and away from said table to bring said press shoe into pressural engagement with said cover; means for exerting a force of substantially constant value between said cross head and said press shoe, said force opposing said yielding movement in all the positions of said press shoe relative to said cross head; and means for securing a strap across the cover of said box, while pressure is being applied to said cover by said shoe, said means being actuated by continued relative movement of said table and cross head after said press shoe has engaged said box.

8. In a machine for applying straps to covers of boxes, the combination of: a table for supporting a packed box having a cover disposed thereover; a press shoe; means suspending said press shoe from said cross head for yielding movement relative to said cross head; means for reciprocating said cross head toward and away from said table to bring said press shoe into pressural engagement with said cover; means for exerting a force of substantially constant value between said cross head and said press shoe, said force opposing said yielding movement in all the positions of said press shoe relative to said cross head; means on said press shoe for supporting a strap disposed across the cover of said box; means on said press shoe for securing the ends of said strap to said box; and means actuated by continued relative movement of said table and cross head after said yielding movement starts for operating said strap securing means.

9. In a machine for strapping a cover on an overfilled packed box, the combination of: a table for supporting said packed box in upright position with a cover positioned thereover; means to confine opposite end portions of a strap in a given plane intersecting said cover and said box; a member extending across said cover and rigidly uniting said aforementioned means, said means and said member comprising a unitary strap support; means for causing relative vertical movement between said strap support and said table to position a strap across said cover; and means for securing the opposite ends of said strap to the opposite sides of said box when the strap is so positioned.

10. In a machine for strapping a cover on an overfilled packed box, the combination of: a table for supporting said packed box in upright

- position with a cover positioned thereover; means to confine opposite end portions of a strap in a given plane intersecting said cover and said box; a member extending across said cover and rigidly uniting said aforementioned means, said means and said member comprising a unitary strap support; means for causing relative vertical movement between said strap support and said table to position a strap across said cover; and means provided on said strap support for securing the opposite ends of said strap to the opposite sides of said box when the strap is so positioned.
11. In a machine for strapping a cover on an overfilled packed box, the combination of: a table 15 for supporting said packed box in upright position with a cover positioned thereover; a rigidly unitary inverted U-shaped strap support mounted over said table, said support having a relatively 20 deep mouth adapted to receive the cover and a substantial upper portion of a box resting on said table, there being guideways on said support to confine a strap in a given plane intersecting said cover and said box; means for causing relative 25 vertical movement between said support and said table to position a strap confined in said support across the cover of said box, and with its ends opposite the sides of said box; and means for securing ends of said strap to sides of said box.
12. In a machine for strapping a cover on an overfilled packed box, the combination of: a table 30 for supporting said packed box in upright position with a cover positioned thereover; a rigidly unitary inverted U-shaped strap support mounted over said table, said support having a relatively 35 deep mouth adapted to receive the cover and a substantial upper portion of a box resting on said table, there being guideways on said support to confine a strap in a given plane intersecting said cover and said box; means for causing relative 40 vertical movement between said support and said table to position a strap confined in said support across the cover of said box, and with its ends opposite the sides of said box; and means provided on said support for securing ends 45 of said strap to sides of said box.
13. In a machine for strapping a cover on an overfilled packed box, the combination of: a table 50 for supporting said packed box in upright position with a cover positioned thereover; means to confine opposite end portions of a strap in a given plane intersecting said cover and said box; an arcuate cover shaping member extending across said cover and rigidly uniting said aforementioned means, said means and said member comprising a unitary strap support and cover shaper; means for causing relative vertical movement 55 between said strap support and cover shaper and said table to arcuately shape said cover and to position a strap thereacross; and means for securing the opposite ends of said strap to the opposite sides of said box when the strap is so positioned.
14. A combination as in claim 6 in which said strap securing means comprises drivers provided on said press shoe; a cam; and cam responsive means carried by said cross head and connected to said drivers for actuating the latter when said cam and said cam responsive means are brought into engagement by the movement of said cross head.
15. In a machine for applying straps to covers of boxes, a table for supporting a box, a cross 10 head disposed above said table, means mounting said table and said cross head for movement toward and away from each other, a press shoe for engaging and applying pressure to said cover of a box when said table and cross head are moved 15 toward each other, means suspending said press shoe from said cross head for yielding movement relative to said cross head, and means for exerting a force of a substantially constant value between said cross head and said press shoe opposing said yielding movement in all positions of said press shoe relative to said cross head.
16. In a machine for applying straps to covers of boxes, a table for supporting a box, a cross 20 head disposed above said table, means mounting said table and said cross head for movement toward and away from each other, a press shoe for engaging and applying pressure to said cover of a box when said table and cross head are moved 25 toward each other, means suspending said press shoe from said cross head for yielding movement relative to said cross head, and means for exerting a force of substantially constant value between said cross head and said press shoe opposing said yielding movement in all positions of said press shoe relative to said cross head.
17. In a machine for applying straps to covers of boxes, a table for supporting a box, a cross 30 head disposed above said table, means mounting said table and said cross head for movement toward and away from each other, a press shoe for engaging and applying pressure to said cover of a box when said table and cross head are moved 35 toward each other, means suspending said press shoe from said cross head for yielding movement relative to said cross head, and means for exerting a force of substantially constant value between said cross head and said press shoe opposing said yielding movement in all positions of said press shoe relative to said cross head, and means for securing a strap across the cover of said box actuated by continued relative movement of said table and cross head after said press shoe has started its yielding movement.
18. In a machine for applying straps to covers of boxes, a table for supporting a box, a cross 40 head disposed above said table, means mounting said table and said cross head for movement toward and away from each other, a press shoe for engaging and applying pressure to said cover of a box when said table and cross head are moved 45 toward each other, means suspending said press shoe from said cross head for yielding movement relative to said cross head, means for exerting a force of substantially constant value between said cross head and said press shoe opposing said yielding movement in all positions of said press shoe relative to said cross head, means on said press shoe for supporting a strap disposed across 50 the cover of said box, means on said press shoe for securing the ends of said strap to said box, and means actuated by continued relative movement of said table and cross head after said yielding movement starts, for operating said strap- 55 securing means.

HERBERT E. TWOMLEY.
